US00D994229S

(12) United States Design Patent (10) Patent No.: US D994,229 S
(45) Date of Patent: * Aug. 1, 2023

(54) FALSE EYELASHES

(71) Applicant: Yunxiao Tian, Shandong (CN)

(72) Inventor: Yunxiao Tian, Shandong (CN)

() Term: 15 Years

(21) Appl. No.: 29/858,226

(22) Filed: Oct. 28, 2022

(51) LOC (14) Cl. 28-04

(52) U.S. Cl.

USPC D28/92

(58) Field of Classification Search

USPC D28/36, 92, 93, 99

CPC . A41G 5/00; A41G 5/02; A45D 44/00; A45D
